FRED C. ANDERSEN, OF BAYPORT, MINNESOTA.

WINDOW FRAME.

Application filed October 12, 1925. Serial No. 62,082.

The object of my invention is to provide one type of window frame in which provision is made for the use of either a narrow or wide blind stop as may be desired by the 5 architect or builder, depending upon the quality of construction used in the building, the narrow stop being designed for use in frame buildings of less expensive construction, the wide stop adding to the expense of 10 the frame, being adapted particularly for use in buildings of the better class to exclude the entrance of air and dust into the building around the window and also to provide a smooth surface with which the sash weight 15 may contact and slide thereon without obstruction.

A further object is to provide a blind stop structure that is adapted for use with a mullion window as well as one of a single type. 20 A further object is to provide a blind stop construction which will not add materially to the cost of the frame and will greatly improve the wall around the window frame as a means for excluding cold air from the 25 building.

The invention consists generally in various constructions and combinations all as hereinafter described and particularly pointed out in the claims.

In the accompanying drawings forming part of this specification,

Figure 1 is a perspective view of a window frame showing a narrow form of blind stop on each side and at the head of the 35 window;

Figure 2 is a similar view showing the frame equipped with a wide blind stop on each side with provision for a wide stop at the head of the window;

Figure 3 is a horizontal sectional view 40 through a window jamb showing the usual method of housing construction where the sheathing terminates at a point remote from the narrow blind stop, allowing opportunity for cold air to enter the building and the projecting ends of the sheathing interfering with the freedom of movement of the sash weights;

Figure 4 is a horizontal sectional view 45 through one jamb of a window frame showing a blind stop of sufficient width to cover the joint between adjacent studding;

Figure 5 is a similar view showing a some-

what narrower type of the wide blind stop, both stops, however, being made from standard or stock lumber;

Figure 6 is a horizontal sectional view showing the wide blind stop feature incorporated in a mullion window frame;

Figure 7 is a horizontal sectional view in which a ship lap joint is shown between the sections of the narrow and wide blind stops in place of the tongue and groove construction;

Figure 8 is a vertical sectional view through the head of a window frame showing the preferred construction of the blind stop at this point.

In the drawing, 2 represents a window frame sill having the standard stops or shoulders 2^a and 2^b thereon. 3 the studding between which the frame is inserted. 4 are the window jambs having the usual parting beads 5, and 6 is the head of the frame opposite to and parallel with the sill. The ends 75 of the sill are suitably notched to receive the lower ends of the jambs and to fit around the studding; all being well known construction in house building.

On the outer edge of each jamb, it has 80 been customary to place a comparatively narrow strip 7 generally designated as a blind stop, its inner edge projecting beyond the face of the jamb about the same distance as the parting bead and forming a seat for 85 the outside blind of the window. Hence, the name "blind stop". The outer edge of the blind stop is concealed in the finished piece of work by the outside casing 8.

As shown in Figure 3, the sheathing is 90 usually laid against the studding and terminates a considerable distance from the narrow blind stop. If the ends of the pieces of sheathing were laid close to the blind stop in an attempt to exclude cold 95 air, an imperfect joint, not an air-tight one, would be formed between the sheathing and the blind stop and the ends of the sheathing would present a rough uneven surface for contact with the adjacent sash weight and 100 interfere materially with freedom of movement of the weight. Generally, therefore, in constructing a building, the sheathing has been terminated at a point on the opposite side of the sash weight pocket from 105 the blind stop, even though such a con-

struction allows considerable cold air to enter the building around the window frame.

To exclude cold air from the building and at the same time provide a smooth vertical grain surface for contact with the sash weights, I provide for an extension of the narrow blind stop consisting of a piece of stock lumber 9 of standard dimensions which may be furnished the builder by any dealer, matched to form a wind-tight abutting joint with the edge of the narrow stop and form a smooth continuation thereof outwardly from the jamb to close that side of the sash weight pocket against the entrance of cold air and form a smooth surface for contact with the sash weight. The narrow stops 7 in the manufacture of the frame are provided with grooves 11 in all cases whether a wide or narrow blind stop construction is to be employed. If the frame is set in the building as shown in Figure 3, then the groove 11 in the narrow stop would have no function, but whenever it is desired to employ the wide blind stop construction, the groove 11 is in position to receive the matched piece of lumber which may be found in the standard stock of all dealers. Thus the frame is readily adapted for use with a narrow blind stop as received from the manufacturer or by the simple addition of a standard piece of lumber on each side of the jamb, a wide blind stop is provided with all the advantages resulting from such a construction. This matched joint between the narrow blind stop and the standard piece of lumber not only serves to exclude dust and wind from entrance to the building around the window frame, but serves to hold the piece of lumber in alignment and in the plane of the narrow stop and facilitates the conversion of the narrow stop frame to one with a wide stop. The piece of board 9 is shown extending outwardly andlapping by the joint of the adjacent studding as this construction may, in some instances, be preferred, the outer edge of the piece of board 9 having the usual groove 12 incidental to matched lumber, with no special function when used as shown in the construction of Figure 2.

In Figure 5, the same structure is shown except that the section 13 of the wide blind stop is narrower than the one shown in Figure 4 so that the outer edge of this section terminates short of the joint between the studding. In both cases, I have shown a tongue and groove joint 14 between the outer edge of the window jambs 4 and the narrow blind stop.

In Figure 6, the invention is shown applied to a mullion type of window, the jambs at the middle of the window corresponding to those on each side and having a vertical piece of board 15 between them

connected by tongue and groove joints 16 with the blind stops which correspond substantially to those heretofore described. These blind stops 7 shown at the center of the mullion window in Figure 6 are partially covered by the outside casing 8^a provided at this point in the window.

In several of the above described figures, I have shown the window jamb rabbeted at 4^a to receive the edge of a casing strip 7^a or board 4^b forming the inner wall of the sash weight pocket. This construction provides for an air-tight joint between the board 4^b and the jamb and aids in preventing cold air from entering the building around the window frame. Generally, this board 4^b is set up against the face of the jamb without any attempt to provide a tight joint. My improvement contemplates an air-tight joint on both sides of the sash weight pocket and embodies a distinct improvement in window construction.

In Figure 7, a modified form of blind stop 7^a is provided having a ship lap joint 17 with the wider section 13^a of the blind stop, in other respects, the structure being substantially the same as described with reference to the other figures. This ship lap joint operates to prevent the cold air from entering the building around the blind stop in substantially the same manner as the tongue and groove construction of the other figures.

In Figure 8, a sectional view is shown of the head of the window frame in which 18 represents the narrow blind stop at the top of the window and 19 a continuation or extension of this stop having a tongue and groove joint 20 therewith. A head 21 of the outside casing covers this stop and the lower edge of the sheathing 22. 23 represents the studding at the head of the frame separating the blind stop from the inside casing 24 and the lath and plaster 25.

The dealer who has in stock a narrow blind stop frame without the groove shown in Figure 3 in the outer edge, has never been in position to furnish this frame for use in a wide blind stop construction without rebuilding the frame. Hence, as a dealer had demand for a narrow blind stop frame and also for one with a wide blind stop, he was compelled to carry two in stock, or what has been generally done, he has been compelled to forego the opportunity of furnishing orders for wide blind stop frames out of his stock on hand and has had them made as a special job. It is generally conceded that the wide blind stop construction is desirable, but it has never been practicable to furnish a regular wide blind stop in one piece as a stock proposition because first, it would add too greatly to the cost of the frame for the builders who did not appreciate the value of a wide blind stop, and sec-

ond the presence of this wide blind stop in a frame was confusing to builders who did not understand its use.

My invention consists in giving to the dealer a frame with a blind stop of the same width as in frames he has always carried and consequently of no greater cost, and which on account of the groove 11 is readily adapted to frames where a wide blind stop is desired. With this construction, I am able to give to the trade a frame having a narrow blind stop and sold at the price of a narrow blind stop frame, which can also be used in the better jobs where a wide blind stop is desired. This invention enables me to furnish one type of frame to the trade that fills two distinct demands which already exist and which has never before been filled by one and the same type of frame. When a dealer attempted to carry as his one and only stock frame at a considerable extra cost, a frame with a solid wide blind stop in one piece, many annoying and expensive mistakes were made by those not familiar with this type of frame. The same dealers who attach enough importance to a wide blind stop to have all of their frames made this way, i. e., with wide stops, will now with my invention be in position to give to the builders who want a wide blind stop frame or who can be shown how to use such a frame, one that is adapted to be used with a wide blind stop, and still have in the same stock a frame that can be furnished to others who are familiar with and want none but the older and cheaper narrow blind stop frame.

It is impracticable for a dealer who wants both types of frames to carry a double stock, as a stock of frames must be very extensive to cover all of the various sizes of windows, doors and casement sash, and to double this stock to be able to give the customer either a narrow blind stop frame or a wide blind stop frame would not be practicable. This is evident by the fact that whereas practically every dealer in the country would agree that a wide blind stop is an excellent construction and they would be glad to be able to furnish it for the better class of jobs, there is no dealer known to the trade who carries any wide blind stop frames on hand except for brick wall construction and for which construction he carries only wide blind stops.

With this invention, it is only necessary to carry one type or style of frame in stock; that is the one with the narrow blind stop having the grooved outer edge. Such a frame is furnished to dealers who want the narrow blind stop construction for less expensive buildings or where no particular pains are taken to exclude cold air and dust around the window frame. Whenever a call is received for a frame with a wide blind

stop, it is only necessary for the dealer to supply stock pieces of lumber having edges adapted to form dust and wind-proof joints with the narrow blind stops and form lateral extensions thereof substantially in the 70 plane of the sheathing. Thus the dealer is able to supply all demands for window frame construction and only be obliged to carry a single type of frame in stock.

I claim as my invention:

1. In a window frame, a narrow blind stop adapted to be inserted between the jamb and the outside casing, and a board wider than said stop and having an edge to edge closed joint therewith and forming a 80 continuation of said stop.

2. A window frame comprising a sill and jambs mounted thereon, narrow blind stops secured to the outer edges of the jambs between them and the outside casing and permanently secured in the window frame when it is built, and stock pieces of boards adapted to be inserted after the frame is built, and having edges to abut the outer edges of said narrow stops and form closed 85 joints therewith and extending outwardly in the plane of the narrow stops to form wide blind stops.

3. A method of making a window frame which consists in placing a narrow strip of 95 material between the outside casing and the jamb to form a narrow blind stop and adapting the outer edge of such strip to form a closed joint with a wider strip of material when inserted between the sheathing and said stop to form with said narrow strip a wide blind stop.

4. A window frame comprising a sill and side jambs thereon, studding spaced from said jambs to form therewith the opposite 105 walls of sash weight pockets, inside and outside casings, narrow blind stops interposed between said jambs and said outside casing, sheathing secured to said studding in the plane of said stops and spaced therefrom, and standard pieces of lumber 110 adapted to form a close joint with said narrow stops and close the gaps between them and said sheathing whereby a window frame with a narrow stop is provided for 115 one type of building or by the addition of standard pieces of lumber, the same frame may be converted to one with a wide blind stop for another type of building construction.

5. A window frame comprising a sill and jambs thereon, inside and outside casings, narrow blind stops interposed between said jambs and said outside casing, said blind stops having outer grooved edges and standard pieces of lumber having tongues on one edge to enter said grooves and form dust and wind-proof joints therewith, and whereby a frame may be used with a narrow blind stop alone in one type of building 130

or the same frame with the addition of standard pieces of lumber will be provided with wide blind stops to adapt the frame for a building of another type.

6. A window frame comprising a sill and side and head jambs therefor, outside casings for said side and head jambs, narrow blind stops interposed between said casings and said side and head jambs, and standard pieces of lumber having their edges abutting the outer edges of said blind stops in the plane thereof and forming closed joints therewith and whereby the same frame is adapted for use with narrow or wide blind stops.

7. A window frame for frame buildings comprising a sill and side jambs thereon, outside casings for said frame, narrow blind stops interposed between the outer edges of the side jambs and said casing and projecting outwardly beyond the front face of said jambs and being flush substantially with back or rear face of said jambs, said blind stops having longitudinal grooves in their rear edges, a studding spaced from said side jambs and cooperating therewith to form walls of sash weight pockets, a sheathing secured to said studding in the plane substantially of said stops, and pieces of matched lumber having tongues to enter the grooves of said blind stops and form wind and dust-proof joints therewith, and also seated on said studding whereby the same frame is adapted for a building of cheaper grade having narrow blind stops

or a building of better grade with wide blind stops.

8. A window frame for frame buildings comprising a sill and side and head jambs therefor, a studding spaced from said side jambs and cooperating therewith to form opposite walls of sash weight pockets, an outside casing having its inner edges flush substantially with the inner faces of said side jambs, comparatively narrow strips forming narrow blind stops interposed between said outside casing and said side jambs in planes at right angles to the plane of said side jambs and having their inner edges projecting beyond the faces of said side jambs and said outside casing, the outer edges of said blind stops having longitudinal grooves therein, a sheathing secured to said studding and spaced from said jambs, standard pieces of lumber adapted to be inserted between said narrow stops and the ends of said sheathing and secured to said studding and having longitudinal tongues to enter the grooves in said narrow stops and form tight joints therewith, whereby standard stock frames equipped with narrow blind stops at the factory for use in cheaper grades of building construction, may by the addition of standard pieces of lumber become adapted without change for use in better grades of building requiring wide blind stops.

In witness whereof, I have hereunto set my hand this 8th day of October, 1925.

FRED C. ANDERSEN.
